UNITED STATES PATENT OFFICE

95,928

DESIGN FOR A STORAGE BATTERY CASE

Oliver O. Rieser, Oak Park, Ill., assignor to The Richardson Company, Lockland, Ohio, a corporation of Ohio

Application March 28, 1935, Serial No. 56,098

Term of patent 7 years

To all whom it may concern:

Be it known that I, Oliver O. Rieser, a citizen of the United States, residing in Oak Park, in the county of Cook and State of Illinois, have invented a new, original, and ornamental Design for a Storage Battery Case, of which the following is a specification, reference being had to the accompanying drawing, forming part thereof.

In the drawing:—

Figure 1 is a perspective view of the storage battery case of my new design showing a side and end panel thereof.

Figure 2 is a view showing an end elevational view on a somewhat reduced scale.

The side and end of the storage battery case not shown in the drawing bear substantially the same design as the side and end illustrated.

I claim:

The ornamental design for a storage battery case, as shown and described.

OLIVER O. RIESER.
